Primary Examiner—A. Hugo Word*Assistant Examiner*—Lavone Tabor*Attorney, Agent, or Firm*—Harold H. Dutton, Jr.; Diane F. Liebman[57] **CLAIM**

The ornamental design for a moisture sensing windshield wiper actuator, as shown and described.

DESCRIPTION

FIG. 1 is a front view of a moisture sensing windshield wiper actuator showing my new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The broken lines showing the windshield wipers are for illustrative purposes only and form no part of the claimed design.
